US00D965002S

(12) **United States Design Patent** (10) Patent No.: **US D965,002 S**
Xu (45) Date of Patent: **** Sep. 27, 2022**

(54) **DISPLAY SCREEN WITH GRAPHICAL USER INTERFACE**

(71) Applicant: **HUAWEI TECHNOLOGIES CO., LTD.**, Shenzhen (CN)

(72) Inventor: **Jie Xu**, Shanghai (CN)

(73) Assignee: **HUAWEI TECHNOLOGIES CO., LTD.**

(**) Term: **15 Years**

(21) Appl. No.: **29/745,912**

(22) Filed: **Aug. 10, 2020**

(30) **Foreign Application Priority Data**

Feb. 11, 2020 (CN) 202030049385.7

(51) **LOC (13) Cl.** **14-04**

(52) **U.S. Cl.**

USPC **D14/485**

(74) Attorney, Agent, or Firm — Rimon PC

(57) **CLAIM**

The ornamental design for a display screen with graphical user interface, as shown and described.

DESCRIPTION

The FIGURE illustrates a display screen with graphical user interface, showing my new design.

The broken line showing of the display screen with graphical user interface is for the purpose of illustrating portions of the display screen with graphical user interface and forms no part of the claimed design.

1 Claim, 1 Drawing Sheet
